US0D1114330S

(12) **United States Design Patent** (10) **Patent No.:** **US D1,114,330 S**
(45) **Date of Patent:** **** Feb. 17, 2026**

(54) **ELECTRONIC CIGARETTE**

(71) Applicant: **KT & G CORPORATION**, Daejeon
(KR)

(72) Inventor: **Han Na Lee**, Daejeon (KR)

(73) Assignee: **KT & G CORPORATION**, Daejeon
(KR)

(**) Term: **15 Years**

(21) Appl. No.: **35/523,836**

(22) Filed: **Jan. 25, 2024**

(80) **Hague Agreement Data**

Int. Filing Date: **Jan. 25, 2024**

Int. Reg. No.: **DM/235410**

Int. Reg. Date: **Jan. 25, 2024**

Int. Reg. Pub. Date: **Jan. 31, 2025**

(30) **Foreign Application Priority Data**

Jul. 27, 2023 (KR) 30-2023-0029239
